UNITED STATES PATENT OFFICE

FREDERICK S. MEYER, OF MINNEAPOLIS, MINNESOTA

DENTAL INSTRUMENT FOR FORMING CERVICAL MARGINS

Application filed March 5, 1928. Serial No. 259,041.

This invention relates to dental instruments and especially to dental instruments for perfecting the gingival margins of wax impressions for interproximal inlays.

5 Ordinarily in forming the wax impression for an interproximal filling the dentist first forces the wax or impression material into the cavity filling up the interproximal spaces between the teeth. The wax is heated before 10 being forced into the cavity and the dentist, of course, endeavors to force the wax as much as possible against the gingival margins of the tooth. Before the wax, however, can be compressed it chills and tends to roll back 15 and pull away from the margins. The excess wax is trimmed from all margins and the wax model is then removed. Usually where the above method is carried out sufficient pressure and heat are not applied adjacent 20 the gingival margins of the tooth to obtain a correct impression and as a result the casting made from the wax model does not perfectly fit the gingival margins.

It is an object of my invention to provide 25 a simple instrument and a method for perfecting the gingival margins of wax models which will obviate the objections above noted and will cause the gingival margins of the wax model to be properly formed adequate 30 heat and pressure being placed upon the wax at points adjacent said margins.

A further object of the invention is to provide 35 a dental instrument so constructed as to be passed between the wax and the tooth adjoining the cavity, or more exactly between the adjoining tooth and a matrix surrounding the wax, which instrument is thin enough to penetrate interproximal spaces and still bulky enough to carry considerable heat and 40 shaped properly to be easily inserted in the manner above described and to draw the gingival edge of the matrix against the adjoining portion of the tooth to be filled.

45 These and other objects and advantages of the invention will be apparent from the following description made in connection with the accompanying drawings wherein like reference characters refer to similar parts throughout the several views and in which:—

50 Figs. 1 and 2 are side elevations of left and

right instruments for forming gingival margins;

Figs. 3 and 4 are plan views of the upper 55 ends of the instruments shown in Figs. 1 and 2;

Fig. 5 is an enlarged side elevation of the tip portion of the instrument shown in Fig. 1; Fig. 6 is a vertical section taken on the line 6—6 of Fig. 5;

Fig. 7 is a view showing the manner in 60 which my instrument is utilized;

Fig. 8 is a view showing the manner in 65 which the instrument is applied and passed between the matrix and the interproximal tooth; and

Fig. 9 is a plan view of the usual matrix used in forming wax models.

As shown in the drawings, two instruments are provided which may be designated as rights and lefts, each comprising an elongated shaft or handle 10 which is usually straight having a diminished working end 10^a provided with a skewed laterally projecting blade 11. Blade 11 is of wedge-shaped cross section conforming in shape to the interproximal spaces between the teeth as shown in Fig. 6 and is slightly curved, tapering from the working end 10^a of the handle to a sharp point 11^a at the outer extremity thereof. The blade is so formed that the thinner 70 concave edge 11^b thereof is adapted to extend towards the occlusal surface of the tooth when applied, while the thickened concave edge is disposed adjacent the gum, the blade being curved to permit the instrument to reach beyond the gingival margin of the cavity with the least mutilation of the gum tissue on the buccal and lingual. The sides of blades 11 taper gradually from the place of connection of the blade with the handle to the point 75 11^a. All edges of the blade are rounded to prevent the blade from cutting and mutilating the gum tissue or scraping the teeth.

The skew in the blade is formed by turning the blade on its longitudinal axis through 80 an acute angle with the thickened convex edge disposed outwardly in order that when the shank or handle is held at an acute angle with the occlusal surface of the teeth and the blade is disposed in an interproximal space, 85 90 95 100

the major portions or surfaces of the blade will touch the surfaces of the approximating teeth, or, as will hereinafter be set forth, the surface of a matrix applied to the approximating teeth.

5 As shown in Fig. 8, one of my instruments is applied between interproximal teeth of a lower jaw, a thin matrix of the type illustrated in Fig. 9 is used in connection with my instrument and has an important function in my method for perfecting gingival margins for wax impressions. Matrix M is first inserted between interproximal teeth. My instrument is then applied as shown in Fig. 8 handle 10 of a right instrument being disposed in inclined position and the blade 11 is passed inwardly between the matrix and the adjacent side of the interproximal tooth next to the tooth to be filled.

10 Previous to the application of the matrix and instrument warm impression material is first forced in the cavity and between the interproximal spaces of the tooth to be filled. Then as shown in Fig. 7 the gingival edge of 15 the matrix M is positioned slightly below the gingival margin of the tooth. My instrument is then applied having first been heated and pressure is placed against the matrix at the gingival margin or slightly below, the matrix being drawn inwardly against the tooth. The wax is thus efficiently forced against the gingival margins and slightly toward the root of the tooth, producing a true impression. This process is followed for the opposite side of the tooth and is repeated at the distolingual, mesiobuccal and mesiolingual angles.

20 The blade 11 of the instrument is thin enough to penetrate interproximal spaces and still bulky enough to carry considerable heat. The blade is curved so that its thickened convex edge will touch the gingival margin of the cavity without lacerating the gingival on the buccal and lingual. When lateral pressure is applied on the blade, due to its structure, the major portion of the opposing surface of the blade will contact with the surface of the matrix. The wax is thus softened and forced over the gingival margins leaving the 25 matrix in the position shown at b in Fig. 7, with a very small amount of excess wax at the gingival margins which can be easily trimmed away. The wax pattern is completed with whatever technique is desired it being advisable to hold the wax pattern steady while trimming to avoid raising the same from the gingival margin.

30 From the foregoing description it will be seen that by the use of my improved instrument in the manner above described, wax models for interproximal inlays may be obtained having substantially perfect gingival margins. The application of heat and pressure to the matrix adjacent the gingival margins forces the wax inwardly as well as in the

direction of the gums and causes a correct impression of the margins to be made. My instrument is especially shaped for insertion in the manner described, the cross section being of wedge shape and the blade portion being curved to permit the matrix to be drawn inwardly.

35 It will, of course, be understood that various changes may be made in the form, details, arrangement and proportions of the parts without departing from the scope of the invention.

What is claimed is:

1. The method of perfecting the margins of wax impressions for interproximal inlays which consists in forcing warm impression material between interproximal teeth, inserting a thin strip of conductive material between the interproximal teeth and against said impression material and applying simultaneously heat and pressure against the edge of said strip adjacent the root of the tooth.

2. The method of perfecting the margins of wax impressions for interproximal inlays which consists in forcing softened impression material in the interproximal spaces of a tooth to be filled, inserting a thin strip of conductive material between said impression material and a tooth adjacent said first mentioned tooth, said strip extending to the root side of the gingival margins of the tooth to be filled and applying simultaneously heat and pressure against said strip of material in the direction of the tooth to be filled, the point of application being adjacent the gingival margins of said last mentioned tooth.

3. A dental instrument for perfecting the margins of wax impressions for interproximal inlays, comprising an elongated shank, a portion of which constitutes a handle, a blade projecting laterally from one end of said shank and tapering gradually from its place of connection with said shank to a well defined point, said blade being substantially triangular in cross section to conform as nearly as possible to the shape of the interproximal spaces of the teeth and being curved with its thickened edge disposed outwardly to prevent laceration of the gums, said blade being also turned with respect to said shank on its longitudinal axis through an acute angle in order that when the shank is held at an acute angle with the occlusal surface of the teeth the blade will fit an interproximal space of the teeth, the edges of said blade being rounded to prevent cutting of the gums or tissue.

In testimony whereof I affix my signature.

FREDERICK S. MEYER.
